UNITED STATES PATENT OFFICE

129,956

DESIGN FOR A SERVING TONGS OR SIMILAR ARTICLE

Rudolph Bernhardt, Chicago, Ill.

Application February 27, 1941, Serial No. 99,256

Term of patent 3½ years

To all whom it may concern:

Be it known that I, Rudolph Bernhardt, a citizen of the United States and resident of Chicago, in the county of Cook and States of Illinois, have invented a new, original, and ornamental Design for a Serving Tongs or Similar Article, of which the following is a specification, reference being had to the accompanying drawing, forming part thereof.

In the drawing:

I claim:

The ornamental design for a serving tongs or similar article, as shown.

RUDOLPH BERNHARDT.
